END STOP FOR SLIDE FASTENERS

Alfred E. Carlile, Great Neck, N. Y., and Alexander M. Brown, Spring Lake Heights, N. J., assignors to Talon, Inc., a corporation of Pennsylvania

Application September 23, 1944, Serial No. 555,440

3 Claims. (Cl. 24—205.11)

1

This invention relates to slide fasteners and, particularly, to an improved end stop therefor for limiting the movement of the slider along the fastener.

In the application of slide fasteners to certain garments, for example, trousers and the like, it is the customary practice to construct the garment in complete halves or parts with a slide fastener stringer attached to each of the respective opposed parts or leg halves, and thereafter to join the two leg halves or parts together. In such constructions, it is necessary to connect the bottom ends of the stringers after the leg halves or parts have been secured together. In other words, a permanent bottom end stop must be applied to the stringers of the slide fastener at or adjacent the ends of the series of interlocking fastener elements so as to connect securely together the bottom end of the stringers, which stop acts to limit the movement of the slider at that end of the fastener in a well-known manner.

Heretofore, various types of connecting means or end stops have been suggested and used for attaching such stringer ends together. While some of these connecting means or end stops were satisfactory in their use, oftentimes, they were unsatisfactory in that they were difficult to apply and usually required the need of special tools or other equipment for applying the same. Usually in such applications, especially in the case of trouser flies, where the bottom ends of the stringers have to be joined near the crotch of the trousers, there is not sufficient space in which to work conveniently, due primarily to the trouser construction. Due to such crowded working space, difficulty is oftentimes experienced in properly applying such proposed end stops or connecting means to the ends of the fastener stringers, and furthermore, after such end stops were applied, a bulky appearance would result. Also, oftentimes, such end connecting means or end stops were fragile in their construction and became either disengaged from the stringers or otherwise failed, thereby defeating the purpose for which they were intended and, eventually, the fastener failed and became inoperative, due to such failure of the end stops.

In the present invention, there is provided an end stop which can be applied properly to such garments in a minimum amount of time with the least amount of effort, without the necessity of any special tools or other equipment, and at the same time, a neat fastener applica-

2

tion is provided, thereby eliminating all of the above disadvantages.

Accordingly, it is one of the objects of the present invention to provide such an end stop which may be readily applied after the two parts of the article or garment are substantially completely made and finished, each with its tape carrying the fastener elements and joined by the slider, thus enabling each part to be completed separately and independently of the other part.

It is another object of the invention to provide an improved end stop for slide fasteners which is simple and inexpensive in its construction, and, at the same time, one which is efficient and effective in its use.

It is a further object of this invention to provide an improved end stop for slide fasteners which can be easily and conveniently applied to the fastener and which will securely grip the material to which it is attached; and at the same time, one which is strong and rugged in its construction so as not to bend under stress.

It is still another object of the present invention to provide an end stop for slide fasteners which is universal in its use in that it may be applied to the fastener at any point therealong and may be used not only as a bottom stop, but also may be used at the upper or top end of the fastener as a so-called bridge-type top stop.

Various other objects and advantages of this invention will be more apparent in the course of the following specification, and will be particularly pointed out in the appended claims.

In the accompanying drawings, there is shown for the purpose of illustration, one embodiment which our invention may assume in practice.

In these drawings:

40. Fig. 1 is a plan view of a slide fastener showing our improved end stop incorporated therewith as a bottom stop;

Fig. 2 is a side view of the fastener, as shown in Fig. 1;

45. Fig. 3 is a bottom end view of the fastener as shown in Fig. 1;

Fig. 4 is a sectional view taken on line 4—4 of Fig. 1;

Fig. 5 is a plan view of the upper end of a slide fastener showing our improved end stop incorporated therewith as a bridge-type top stop; and

Fig. 6 is a perspective view of the improved end stop of the present invention.

Referring more particularly to the drawings, there is shown in Fig. 1 a conventional type

3

slide fastener comprising cooperating series of spaced-apart interlocking fastener elements 2, attached to opposed beaded edges of tapes or stringers 3. There is supported on the series of interlocking fastener elements, a slider 4 for longitudinal movement therealong in opposite directions to open and close the fastener in a well-known manner. Such a slider consists generally of spaced-apart upper and lower wings 5 and 6, respectively, having inwardly extending flange portions or sides 7 connected by a neck 8 so as to provide substantially a Y-shaped channel body member. There is carried by the top wing 5 of the slider, in the present instance, a longitudinally extending lug 9, to which a pull member 10 is pivotally and slidably attached for manipulating the slider.

The improved end stop of the present invention, as more clearly shown in Fig. 6 of the drawings, comprises substantially a U-shaped member 12 preferably formed from a piece of either round, square or semi-circular-shaped wire which is bent so as to provide a pair of spaced-apart leg portions 13 and a central connecting portion 14 with each of the leg portions arranged preferably obtusely to the central connecting portion. The central connecting portion 14 is preferably offset from the leg portions 13 so as not to be in the same plane therewith for a purpose hereinafter to be described. Each end portion of the wire is bent, as at 15, back upon its respective leg portion 13 and extends substantially the length thereof with the extreme end terminating preferably adjacent the central connecting portion 14 so as to provide a hook-like attaching portion 16 on each of the leg portions. Each of the extreme ends of the wire is preferably pointed or has a sharpened edge, as at 17, and there is arranged on each of the hook-shaped portions 16 on the side thereof adjacent their respective leg portions 13 at a point near the pointed ends 17, preferably a knurled or irregular surface, such as a barb 18.

Our improved end stop is applied to the fastener in the following manner. After the stringers have been assembled with the interlocking fastener elements engaged with each other, the end stop is positioned at the bottom end of the fastener or at the point therealong at which it is desired that it be attached thereto, with the leg portions 13 thereof disposed to either side of the fastener elements and extending toward that portion of the fastener on which the slider is assembled, with the central connecting portion 14 disposed substantially parallel to the fastener elements. In positioning the end stop on the fastener, the pointed ends are disposed so that they will pass through the fabric when the fastener and end stop are moved relative to each other so that the hook-shaped attaching portions 16 will engage the fabric of the fastener. The fastener and end stop are then moved relative to each other and it will be seen upon such movement, that the sharp pointed ends 17 of the stop will penetrate and pass through the tape stringer or material bordering the opening. Upon continued movement of the end stop relative to the fastener, it will be seen that the bends 15 in the ends of the leg portions will finally be disposed at the point where the pointed ends 17 penetrated the fabric or material. After the end stop has been positioned on the fastener in such a manner, it will be seen that the barbs 18 on the extreme ends of the hook-shaped portions project or dig into the material or fabric along the opening

4

thereby preventing displacement of the end stop from its assembled position on the fastener, as shown in Figs. 2 and 3.

It will be understood that our improved end stop, due to the construction thereof, may be applied to the bottom end of the fastener, as shown in Fig. 1 of the drawings, or may be applied to the fastener at any point therealong, or may be used as a bridge-type top stop, as shown in Fig. 5 of the drawings, for connecting together the fastener stringers at the upper or closing end of the fastener, so as to act as a top stop. It will be understood also that it is not absolutely necessary that the endmost fastener elements at the bottom of the fastener be evenly meshed in order that the end stop of the present invention be applied thereto. In other words, as shown in Fig. 1, the fastener elements on one stringer may extend below the fastener elements on the other stringer and in such case, it will be understood that the end stop is applied to the fastener so that the central connecting portion 14 thereof is disposed in the vicinity of the endmost fastener element on the shorter stringer. When the end stop is applied in such a manner, it will be seen that the cross bar or central connecting portion 14 rests upon the upper side of the endmost fastener elements. This central connecting portion 14 is preferably offset from the leg portions 13 so that the leg portions will lie flat against the stringer or material rearwardly of the fastener elements when the cross bar or central connection 14 rests upon the fastener elements, as shown in Figs. 2, 3 and 4. By providing such a construction, the leg portions together with the central connecting portion prevents disengagement of the endmost fastener elements disposed between the leg portions when this portion of the fastener is subjected to lateral stress.

After the end stop has been attached to the fastener, as above described, it will be seen that the leg portions 13 are disposed angularly relative to the fastener elements 2, as shown in Fig. 1, and that they penetrate the material or stringer rearwardly of the fastener elements and at a spaced distance therefrom. This spacing of the leg portions from the outer ends of the fastener elements is provided so as to permit the slider to pass to a position between the leg portions 13 of the stop, as shown in the broken lines of Fig. 1 of the drawings. By providing such an arrangement, it will be seen that the slider is permitted to move the full length of the fastener so as to provide a full opening thereof. It will be seen that when the slider is moved to its fully open position between the leg portions 13 of the end stop, that the flange portions or side walls 7 of the slider contact the leg portions and that the lower end of the slider contacts the central connecting portion 14. In other words, the leg portions 13 cooperate with the flanges 7 and the central connecting portion 14 cooperates with the lower end of the slider to prevent further movement of the slider along the fastener in an opening direction. If desired, the leg portions 13 may be designed or formed so as to conform substantially to the side walls or flanges of the slider, so as to fit around the outer contour thereof.

In case the end stop of the present invention is used as a bridge type top stop, as shown in Fig. 5 of the drawings, it will be understood that it is applied to the fastener in substantially the same manner as if it were to be used as a bottom stop with the hook-shaped portions of the legs 13 penetrating the fabric or the material at a

point adjacent the endmost fastener elements at the upper or closing end of the fastener. It will be seen that the end stop in being substantially U-shaped, conforms to the upper end of the slider and cooperates with the neck portion 8 and the upper end of the slider to limit the upper or closing movement thereof.

As a result of our invention, it will be seen that there is provided an end stop which may be quickly and conveniently applied to the fastener with the least amount of effort. One of the most important aspects of this invention is that the end stop can be applied to the bottom of the fastener without the necessity of ensuring that the endmost fastener elements of the stringers are even. In other words, if one stringer is longer than the other, it is not necessary that the fastener elements be removed from one of the stringers as in most cases, in order to apply our improved end stop. This is due to the fact that the cross bar or central connecting portion 14 will conveniently extend over the top of the fastener elements.

It will be seen that our improved end stop is designed in such a manner that a series of them may be conveniently held together in a group by lacquer or some other suitable adhesive so as to provide a strip of end stops in a manner similar to staples. In such a case, the strip of end stops could be fed from a magazine and the endmost stop of a strip, while still attached to the strip, could then be easily assembled on the fastener merely by forcing the pointed ends of the end stop through the fabric thereby attaching the endmost stop thereto. The fastener together with the endmost stop attached thereto could then be merely pulled from the ends of the strip of stops so as to disengage the endmost stop therefrom. Thus, it will be seen that no tools whatsoever are necessary for assembling or attaching the end stop of the present invention to the fastener which is another important advantage of our invention.

While we have shown and described one embodiment which our invention may assume in practice, it will be understood that this embodiment is merely for the purpose of illustration and description, and that various other forms may be devised within the scope of our invention as defined in the appended claims.

What we claim as our invention is:

1. An end stop for slide fasteners of the class described, including a series of spaced interlocking fastener elements arranged along the opposed edges of a pair of stringer tapes and a slider mounted thereon for engaging and disengaging the same, consisting of a substantially U-shaped member having a pair of leg portions and a central connecting portion, fabric penetrating attaching means carried by each of said leg portions, said leg portions adapted to be positioned to either side of the fastener elements with attaching means penetrating the stringer tapes rearwardly of said fastener elements and with the open end of said U-shaped member disposed toward the slider with the central connecting portion arranged substantially parallel to the fastener elements whereby the slider is adapted

to pass between said leg portions and be seated in the open end of said U-shaped member when it is moved to that end of the fastener at which the stop is positioned.

5 2. An end stop for slide fasteners of the class described, including a series of spaced interlocking fastener elements arranged along the opposed edges of a pair of stringer tapes and a slider mounted thereon for engaging and disengaging the same, consisting of a substantially U-shaped member formed from a piece of wire so as to provide a pair of leg portions and a central connecting portion, the ends of said wire being bent back upon the respective leg portions so as to provide a hook-shaped attaching portion on each of said leg portions, said leg portions adapted to be positioned to either side of the fastener elements with the hook-shaped attaching portions thereof penetrating the tapes rearwardly of said elements and with the open end of said U-shaped member disposed toward the slider and with the central connecting portion of said stop arranged substantially parallel to the fastener elements whereby the slider is adapted to pass between the leg portions and be seated in the open end of said U-shaped member when it is moved to that end of the fastener at which the stop is positioned.

10 3. An end stop for slide fasteners of the class described, including a series of spaced interlocking fastener elements arranged along the opposed edges of a pair of stringer tapes and a slider mounted thereon for engaging and disengaging the same, consisting of a substantially U-shaped member formed from a piece of wire so as to provide a pair of leg portions and a central connecting portion, the ends of said wire being bent back upon the respective leg portions and passing through the tapes on each side of the fastener so as to provide hook-shaped attaching portions on each of said leg portions with the ends of said wire extending substantially the full length of said leg portions and the extreme ends terminating adjacent said central connecting portion, said leg portions adapted to penetrate said tapes on either side of the fastener rearwardly of the fastener elements with the open end of said U-shaped member adapted to be disposed toward the slider and with the central connecting portion disposed substantially parallel thereto whereby the slider is adapted to pass between the leg portions and be seated in the open end of said U-shaped member when it is moved to that end of the fastener at which the stop is positioned.
